His Attorney.

UNITED STATES PATENT OFFICE

EDWARD W. KELLOGG, OF SCHENECTADY, NEW YORK, ASSIGNOR TO GENERAL ELECTRIC COMPANY, A CORPORATION OF NEW YORK

ELECTROMAGNETIC DEVICE

Application filed December 3, 1926. Serial No. 152,475.

The present invention relates to electro-magnetic devices, and more particularly to the type of sound reproducing devices commonly known as loud speakers.

5 One of the objects of my invention is to provide a vibratory system, employing a movable iron armature and a diaphragm, having a low natural period of vibration.

While various attempts have been made 10 to secure a vibratory system having a low natural period, it has been difficult to accomplish such a result when employing iron armatures owing to the fact that the vibrating armature is usually unstable in the magnetic field unless held by means of a stiff spring. The magnetic pull tending to displace the armature varies with the position of the armature in the field and increases very rapidly as the armature approaches either 15 polepiece. If it were possible to balance the magnetic pull against the spring action of the armature, a vibratory system having a very low natural period could theoretically be obtained, but owing to the changing slope 20 of the magnetic pull curve it is difficult to obtain a close balance.

While it is possible to obtain a close balance between the magnetic pull and the spring action by the employment of springs whose 25 stiffness increases with deflection, I have found that a very close balance may be obtained with a simple spring and a rocking armature by restricting the flux in the magnetic system so that the sum of the fluxes 30 through the armature is practically constant. With a constant total flux the force deflection curve becomes substantially a straight line. An arrangement of this character possesses advantages over an arrangement in 35 which springs of varying stiffness are employed to balance the pull on the armature. A close balance between spring stiffness and magnetic pull calls for a high degree of uniformity in magnetic strength in order that 40 identical springs may give uniform results in different instruments. While it is difficult to make a large number of magnets which will be substantially equal in strength, it is possible by the use of saturated pole 45 pieces to obtain better uniformity in the total

amount of flux employed, since the amount of magnetic flux which a piece of soft iron will carry is substantially constant.

The novel features which I believe to be characteristic of my invention are set forth 55 with particularity in the appended claims. My invention itself, however, will best be understood from reference to the following specification taken in connection with the accompanying drawings in which Fig. 1 is a 60 perspective view of a loud speaker diaphragm and motor which embody the features of my invention; Fig. 2 is a front elevation of the magnetic system shown in Fig. 1; Fig. 3 is a 65 curve illustrative of the relation which ordinarily exists between the magnetic force tending to deflect a diaphragm and the deflection of the diaphragm; Fig. 4 is an exploded view of the polepieces and the mounting for the armature and the coils cooperat- 70 ing therewith; while Fig. 5 is an enlarged view of a portion of the motor shown in Fig. 1.

Referring to the drawings, I have indicated at 1 a cone-shaped diaphragm which 75 is adapted to vibrate as a whole. The diaphragm may be mounted in any suitable manner in a cabinet having a front panel 2 provided with an opening 3. The diaphragm is actuated by means of a motor 80 comprising a permanent magnet 4 which is provided with soft iron polepieces 5 and 6. A flat elongated armature 7 is mounted on a relatively stiff spring 8 which is attached 85 at its opposite ends to brass or otherwise suitable non-magnetic supporting members 9 and 9'. One end of the polepiece 5 is secured to the permanent magnet 4 by means of a bolt, while the other end of the polepiece is secured to a lug 10 on the non-magnetic member 9. The intermediate portion of the polepiece 5 is connected to the member 9'. As thus arranged the pole tips 11 and 12 of the polepiece 5 fit in an opening 13 between the members 9 and 9' and extend 90 toward the armature 7, as clearly indicated in Fig. 1. Polepiece 6 is secured in a similar manner to the magnet 4 and to the opposite side of the supporting members 9 and 9', 95 the lower end of the polepiece 5 being se- 100

cured to a lug 14 on member 9', while the intermediate portion of the polepiece 6 is secured to member 9. Coils 15 and 16 surround the armature 7, members 9 and 9' being rounded, as indicated at 17 and 18 to accommodate the coils 15 and 16 respectively. Armature 7 is connected to the diaphragm 1 by means of a drive rod 19 which is flattened at the end adjacent the armature, as indicated at 20 in Fig. 1 and on an enlarged scale in Fig. 5. When current is supplied to coils 15 and 16 armature 7 is actuated and the diaphragm 1 is vibrated.

The polepieces 5 and 6 are provided with constricted portions 21 between the magnet 4 and the pole tips 11 and 12. When the device is assembled the portions 21 become substantially saturated and thereby limit the total flux which passes through the pole tips 11 and 12 in multiple, to a practically fixed value. When the armature rocks so that one end approaches pole tip 12 and the other end recedes from 11, for example, the decrease in air gap reluctance opposite 12 more than offsets the increased reluctance opposite 11. If an approximately constant magnetic potential were maintained between the pole tips of 5 and those of 6, as would be the case in the absence of the saturated necks 21, the increase of flux from pole tip 12 would be greater than the decrease of flux from 11. Under these conditions the magnetic moment on the armature bears a non-linear relation to deflection or tip of the armature, as illustrated in Fig. 3. On the other hand, if the sum of the magnetic fluxes from 11 and 12 is constant, the force or magnetic moment bears a straight line relation to the deflection of the armature. Such an arrangement is easily stabilized and provides a close balance between magnetic pull and the spring action of the armature.

Magnetic flux which leaks across from 5 to 6 through paths other than across the working air gaps, tends to reduce the effectiveness of the saturated necks in holding the sum of the fluxes in the working air gaps constant, since a reduction in reluctance of the working gaps causes a diversion of some of the leakage flux to the low reluctance gap. It is therefore desirable that the total amount of leakage flux shall be as small as possible compared with the useful flux. To this end I have designed the device shown, in such a way that the working air gaps have a much lower reluctance than is usual with this type of motor. I accomplish this by making the poleface areas, or surfaces of the pole tips 11 and 12 next to the armature, larger than has been the case in most earlier designs, while the air gap length, or clearance between armature and pole tips is about the same as has been generally used namely from .010 to .015 inch.

Although saturation in the armature itself

would assist stabilization, I have found that where an armature having a cross-section small enough to accomplish this purpose is employed it is too easily saturated and loss of sensitivity results. On the other hand the use of pole-pieces with saturated necks does not in any way impair sensitivity. In the present instance the armature is approximately $\frac{1}{4}$ inch in width and the air gap area employed at least $\frac{1}{8} \times \frac{1}{4}$ inches. It is important that the armature 7 be well centered and it is desirable that the polefaces of the parts 11 and 12 be so shaped that as the armature approaches a polepiece the co-operating surfaces of the armature and pole-piece are substantially parallel rather than making a point contact. This arrangement prevents a concentration of flux at any point which would cause an augmented pull on the armature.

The foregoing arrangement provides a drive having great flexibility and when employed with free edged cones the fundamental resonance is very low. For the purpose of further increasing the flexibility of the system from the standpoint of obtaining low natural frequency the rocker arm or armature 7 may be so proportioned that the motion of the vibrating cone or diaphragm 1 is greater than the motion of the armature 93 in the air gaps. There is a limit to the advantage which may be obtained by stepping up the motion of the diaphragm. I have found, however, that a step-up movement which is slightly greater than 2 to 1 provides 100 a marked advantage, although a step-up of less than 2 to 1 gives no appreciable advantage.

In addition to having a flexible rocker spring, it is advantageous to have sufficient 105 flexibility in the drive rod 19 so that the stiffness of the system is not materially increased by the stiffness of the drive rod. This flexibility may be obtained by flattening the drive rod at the end adjacent the rocker arm, 110 as indicated at 20 in Figs. 1 and 5.

With the drive of the type above described and a paper cone having a thickness of .006 inches and a diameter of $5\frac{3}{4}$ inches it will be found that the fundamental resonance of 115 the system (in which the cone constitutes the principal mass and the springs in the driving mechanism constitute the principal restoring force) is below 200 cycles per second and will average about 140 cycles per second. 120

What I claim as new and desire to secure by Letters Patent of the United States, is:—

1. In combination, a magnetic structure comprising an armature, a magnet, a pole piece connected to the magnet and adapted 125 to complete a magnetic circuit through the magnet and armature, said pole piece comprising a pair of pole tips of like polarity, means for vibrating the armature, a spring adapted to hold the armature in its normal 130

position, said armature being of such cross-section as to prevent saturation thereof, the portion of the pole piece between the pole tips and magnet being constantly magnetically saturated, whereby a straight line relation may be maintained between the deflection of the armature and the force tending to deflect it.

2. In combination, a magnetic structure comprising an armature, a magnet, means for completing a magnetic circuit through the armature and magnet, said means comprising a pole piece having a pair of pole tips of like polarity, means for vibrating the armature, a spring adapted to hold the armature in its normal position, said armature being of such cross-section as to prevent saturation thereof, and means for maintaining the sum of the fluxes through the armature from the pole tips of like polarity substantially constant, said means comprising a constantly saturated portion in the magnetic circuit.

3. In combination, a magnetic structure comprising an armature, a magnet producing a force on the armature, means for vibrating the armature, a spring adapted to hold the armature in its normal position and a pair of pole pieces secured at one end to said magnet and cooperating with opposite sides of said armature, said armature being of such cross-section as to prevent saturation thereof, said pole pieces each having at the other end thereof, a pair of pole tips of like polarity, the portion of said pole pieces intermediate the ends being constantly magnetically saturated.

4. A vibratory system having a resonance frequency below 200 cycles per second and including means for producing a substantially constant magnetic flux in an air gap having an area of not less than $\frac{1}{32}$ square inch, said means comprising a constantly saturated flux-conducting element, a diaphragm, and an armature connected to said diaphragm and vibratable in said gap, said armature being of such cross-section as to prevent saturation thereof.

In witness whereof, I have hereunto set my hand this 2nd day of December, 1926.

EDWARD W. KELLOGG.
